DESIGN FOR A TOY

Vincent Lorenzi, East Bethany, N. Y.

Application August 29, 1933. Serial No. 49,163

Term of patent 3½ years

To all whom it may concern:

Be it known that I, VINCENT LORENZI, a citizen of the United States, residing at East Bethany, in the county of Erie and State of New York, have invented a new, original, and ornamental Design for a Toy, of which the following is a specification, reference being had to the accompanying drawing, forming part thereof.

I claim:—

The ornamental design for a toy as shown.

VINCENT LORENZI.
